UNITED STATES PATENT OFFICE.

CLARENCE D. PLATT, OF BRIDGEPORT, CONNECTICUT.

ELECTRICAL KEY-SOCKET.

No. 920,179.

Specification of Letters Patent.

Patented May 4, 1909.

Application filed September 16, 1908. Serial No. 453,348.

To all whom it may concern:

Be it known that I, CLARENCE D. PLATT, a citizen of the United States, residing at Bridgeport, county of Fairfield, State of Connecticut, have invented a new and useful Electrical Key-Socket, of which the following is a specification.

This invention has for its object to simplify and cheapen and to generally improve the construction and operation of electrical key sockets.

With these ends in view I have devised the novel construction which I will now describe, referring to the accompanying drawing forming a part of this specification and using reference characters to indicate the several parts:

Figure 1 is a vertical section of my novel socket showing the parts in position to close the circuit; Fig. 2 a vertical section on the line 2—2 in Fig. 1, looking in the direction of the arrows, the circuit being open; Fig. 3 an inverted plan view of the screw shell detached; Fig. 4 a section of the screw shell on the line 4—4 in Fig. 3, looking in the direction of the arrows; Fig. 5 an enlarged detail sectional view through the base of the screw shell, showing the attachment of the insulating washers and springs thereto; and Fig. 6 is a detail sectional view of the shaft and bracket, showing the closing block in elevation.

10 denotes an insulating body which is provided with a recess 11 to receive the switch mechanism, with a slot 12 for the key shaft and with recesses 13 which receive the terminals.

14 denotes the screw shell whose base is provided with an external depression 15 to receive an insulating washer 16 and with an internal depression 17 to receive an insulating washer 18, the base of the screw shell lying between said washers.

19 denotes a contact spring for engagement by a lamp base, indicated by 20, and 21 a contact spring for engagement by a closing block indicated by 22. Contact spring 19 lies contiguous to insulating washer 18 and contact spring 21 lies contiguous to insulating washer 16. The insulating washers and the contact springs are shown as secured to the base of the screw shell by means of an eyelet 23 which passes through said parts and is headed down upon the bases of the contact springs, as clearly shown in Fig. 5. It should be noted that the base of the screw

shell is provided with a central hole 24 of greater diameter than the eyelet so as to leave the screw shell perfectly insulated from the contact springs.

60 The closing block 22 of the switch is provided with an angular central opening indicated by 25 through which the angular shaft 26 passes loosely so as to permit slight play to the shaft and cause the switch to open and close with a snap. 27 denotes a U-shaped bracket having formed integral therewith a terminal 28, the combined bracket and terminal being secured to the body by a screw 29. The arms of the bracket 65 are provided near their outer ends with corresponding openings 30 through which the angular shaft passes freely, the essential feature of these openings being that they are approximately circular except for a flat portion of each as at 31, said flat portions being adapted for engagement by either of the sides, four in the present instance, of the angular shaft. 32 denotes a coil spring surrounding the arms of the bracket and bearing 70 against the base thereof and carrying at its outer end a clip 33 which is forced by the spring against the closing block. Terminal 28, which is formed integral with the U-shaped bracket, lies in one of the recesses 13 75 in the body. The other terminal, indicated by 34, lies in the other recess 13 in the body and is secured to the body by a screw 35 which also serves as a means of attachment for the screw shell. The other screws by which 80 the screw shell is secured to the body pass through the body longitudinally and are shown in dotted lines only (see Fig. 1). Both of the terminals are provided with binding screws 36 to which circuit wires 37 are connected.

85 The operation will be readily understood from the drawing. Spring 32 and the clip bearing against the closing block act to hold one of the angular sides of the shaft in engagement with the angular sides of openings 30 in the arms of the bracket, thus retaining the closing block in any position in which it may be placed with the circuit either closed or open, as shown in Figs. 1 and 2. In order 90 to insure that when the closing block is moved to the closing position, as in Fig. 1, the angular shaft will not be forced away from the flat portions of the openings in the bracket arms, I provide contact spring 21 for 95 engagement by the block. When the block is turned to the closing position it engages the

contact spring which is weaker than spring 32 and yields so that the engagement of the shaft with the angular sides of the openings in the bracket is not interfered with. When a lamp base is turned into the screw shell, the center contact of the lamp base engages contact spring 19. The passage of the current is from terminal 28 through the bracket, closing block, contact springs 21 and 19 and eyelet 23 to the center contact of the lamp and returning through the lamp base, screw shell and screw 35 to terminal 34.

Having thus described my invention I claim:

- 15 1. In a key socket the combination with a closing block and an angular shaft by which it is carried, of a bracket having openings through which the shaft passes loosely and which openings have flat portions, and means for retaining an angular side of the shaft in engagement with the flat portions of the openings when the closing block is in the open or closing position.
- 20 2. In a key socket, the combination with a closing block and an angular shaft by which it is carried, of a bracket having openings through which the shaft passes loosely and which openings have flat portions, a clip bearing against the closing block and a spring 25 by which the clip is carried, substantially as described, for the purpose specified.
- 25 3. The combination with a screw shell hav-

ing internal and external depressions and a central hole and insulating washers in the depressions, of contact springs contiguous to 35 the washers and an eyelet passing through the springs, washers and screw shell, whereby the parts are secured together.

4. In combination in a key socket, a base of insulating material, a closing block and an 40 angular shaft by which it is carried, a bracket having openings with flat sides through which openings said shaft passes loosely, springs co-acting to keep a flat side of the shaft in engagement with the flat sides of the 45 bracket openings, and a screw shell having yielding contacts mounted therein, substantially in the manner and for the purpose specified.

5. The combination with a closing block 50 having an angular opening and an angular shaft engaging said opening loosely, of a bracket having openings with flat portions through which openings the shaft passes loosely and a spring bearing against the closing block, substantially as described, for the 55 purpose specified.

In testimony whereof I affix my signature, in presence of two witnesses.

CLARENCE D. PLATT.
